(57) CLAIM

The ornamental design for a recreational vehicle vent cover, as shown and described.

DESCRIPTION

FIG. 1 is a front, right, and top perspective view of a recreational vehicle vent cover showing my new design; FIG. 2 is a rear, left, and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken lines in the drawings depict portions of the recreational vehicle vent cover that form no part of the claimed design.
